CLAIM

The ornamental design for a table lamp, as shown and described.

DESCRIPTION

1. Table lamp
  2. Table lamp
- 1.1 is a first perspective view of a first table lamp according to the present invention;
- 1.2 is a second perspective view of the table lamp;
- 1.3 is a bottom perspective view of the table lamp;
- 1.4 is a side view of the table lamp;
- 1.5 is a bottom view of the table lamp.
- 2.1 is a front view of a second table lamp attached to a bottle;
- 2.2 is a front exploded view of the table lamp of 2.1 and the bottle;
- 2.3 is a lower front perspective view of the table lamp of 2.1 and the bottle.

The broken lines are for the purpose of illustrating environmental structure and form no part of the claimed design.

1 Claim, 8 Drawing Sheets
